UNITED STATES PATENT OFFICE.

DELTON I. HOCH, OF COLUMBUS, OHIO.

OIL-BURNER.

1,268,009.

Specification of Letters Patent. Patented May 28, 1918.

Application filed September 14, 1917. Serial No. 191,417.

To all whom it may concern:

Be it known that I, DELTON I. HOCH, a citizen of the United States, residing at Columbus, in the county of Franklin and State 5 of Ohio, have invented a new and useful Oil-Burner, of which the following is a specification.

The device forming the subject matter of 10 this application is adapted to be employed for turning liquid fuel into gas and for burning the gas thus produced, and it is the object of the invention to improve the construction of the priming charge holder, so that the same will be peculiarly efficient in 15 directing the products of combustion derived by burning a priming charge, toward and upon the loop-shaped generating and combustion pipe.

It is within the province of the disclosure 20 to improve generally and to enhance the utility of devices of that type to which the present invention appertains.

With the above and other objects in view 25 which will appear as the description proceeds, the invention resides in the combination and arrangement of parts and in the details of construction hereinafter described and claimed, it being understood that changes in the precise embodiment of the 30 invention herein disclosed can be made within the scope of what is claimed, without departing from the spirit of the invention.

In the accompanying drawings:—

Figure 1 is a side elevation wherein parts 35 appear in section;

Fig. 2 is a top plan;

Fig. 3 is a cross section.

In carrying out the present invention there 40 is provided a base including air flues 1 constituting supports for the lower arm 2 of a loop-shaped pipe 3 the upper arm of which is denoted by the numeral 4. The lower arm 2 has combustion orifices 5 co-operating with the air flues 1, and flame spreaders 6 are 45 mounted on the upper arm 4 above the orifices 5, it being possible to turn the spreaders so as to deflect the flame in different directions.

The air flues 1 are connected by a priming 50 charge holder including walls 7 which converge at any desired angle, upwardly, toward the loop-shaped pipe 3 and, specifically, toward the lower arm 2 thereof. The walls 7 may be supplied with fuel holding 55 seats of any desired kind, the same in the present instance being shown in the form of

longitudinal corrugations 8. If corrugations are employed, the same may be of any desired length, but if the corrugations extend the full length of the walls 7, then the 60 flues 1 constitute closures for the ends of the corrugations. The walls 7 may be covered on their outer surfaces with an incombustible material of any kind such as a layer of asbestos 9. A bracket 10 is secured to one of 65 the walls 7 and engages the upper arm 4 of the pipe 3 to aid in sustaining the pipe.

In practical operation, oil is admitted into 70 the upper arm 4 of the pipe 3 and is converted into gas by the flames burning at the 70 orifices 5, the gas passing into the lower arm 2 and thence to the orifices, where the gas is consumed. Air passes upwardly through the flues 1, in a well known manner.

A priming charge may be deposited in the 75 seats or corrugations 8 of the walls 7, and be ignited, for the purpose of heating the pipe 3 initially. Owing to the fact that the walls 7 converge, as hereinbefore described and shown in the drawings, the flame from 80 the burning priming charge will be caused to converge upon the pipe 3, with peculiar efficiency, a minimum amount of priming material being sufficient to heat the pipe 3 to the desired extent.

Those skilled in the art will understand 85 readily that the device hereinbefore described is of that general type which ordinarily is used in a cook stove.

Having thus described the invention, what 90 is claimed is:—

1. A device of the class described comprising spaced supports; a loop-shaped pipe including an upper arm, and a lower arm carried by the supports and having a combustion orifice; and a priming-charge holder connecting the supports and including walls which converge upwardly and meet below the lower arm of the pipe.

2. A device of the class described constructed as described in claim 1, and further characterized by the fact that the converging walls of the priming charge holder are supplied with charge-holding seats.

3. A device of the class described, comprising spaced supports; a loop shaped pipe including an upper arm, and a lower arm carried by the supports and having a combustion orifice; and a priming charge holder connecting the supports and including walls which converge upwardly toward the pipe, 100 the converging walls of the priming charge

holder being supplied with longitudinal corrugations constituting charge holding seats.

4. A device of the class described, comprising spaced supports; a loop shaped pipe including an upper arm, and a lower arm carried by the supports and having a combustion orifice; and a priming charge holder connecting the supports and including walls which converge upwardly toward the pipe,
10 the priming charge holder being provided with longitudinal corrugations extended the

full length thereof and constituting charge holding seats, the supports forming closures for the ends of the corrugations.

In testimony that I claim the foregoing as 15 my own, I have hereto affixed my signature in the presence of two witnesses.

DELTON I. HOCH.
